DES.
Design No. 20.
Henry Dubois Child's whistle
Patented May 6th 1844.

Dec. 20-

Henry Dubosq, Philadelphia Pennsylvania
Letters Patent No. 20, dated May 6th 1844 ✓

The Schedule referred to in these Letters Patent and making
part of the same. —

Be it known that I Henry Dubosq of the City and
County of Philadelphia and State of Pennsylvania have
invented or produced a new design for what is commonly
denominated a "Childs coral" and I do hereby declare
that the following is a full, clear and exact description there-
of reference being had to the drawing accompanying.

My design consists in forming a whistle of common
construction made of metal, so as to attach a piece of pearl
coral or other proper substance thereto; the whistle (a)
is made round, and its base or lower part spreads out
on each side into the segment of an oval as shown at
(a') in the drawing the lower edge may be scalloped
and an ornamental figure stamped on each side; this
part is hollow and in it is inserted a piece of mother
of pearl, shell (b) or other suitable substance of an oblong
form and rounded at the end — to one side of the
whistle, a ring is affixed by which it is suspended.

What I Claim as my design and for which I de-
sire letters Patent is the combination of the whistle
and pearl — forming the design herein described and
delineated.
